REFINING OF MINERAL OILS BY MEANS OF
ALLOYS OR LOOSELY BOUND COMPOUNDS
OF ALKALI METALS

Evan Clifford Williams and Herbert Peter Augustus Groll, Berkeley, Calif., assignors to Shell Development Company, San Francisco, Calif., a corporation of Delaware

Application August 10, 1929. Serial No. 384,942

7 Claims. (Cl. 196—23)

This invention relates to the refining of mineral and other oils and particularly to the sweetening of cracked products from petroleum, in future referred to as cracked distillate. The invention 5 consists in treating the mineral oil with loose compounds of an alkali metal, or mixtures of such compounds, preferably in a continuous process.

These compounds are defined by the characteristic that they are decomposed by water to the 10 hydroxides of the alkali metal used. Such compounds are, for instance, the amides, alcoholates, amalgams, or alloys of alkali metals.

Further features and advantages of our invention will appear from the following description 15 of one method of carrying the invention into effect. It will be understood that we do not limit ourselves to the details of this particular method of using our invention, but we extend our claims for the principle of our invention as far in scope 20 and equivalents as the state of the prior art will allow.

The present invention is applicable to many oils, especially mineral oils such as petroleum oils or oils derived from coal or shale, but we will 25 describe it particularly with reference to the treatment of cracked distillate obtained by cracking from petroleum oils, which is one of the most difficult petroleum products to refine.

We found that when metallic sodium was placed 30 in cracked gasoline of foul odour, it became coated, in the course of days, with deposits of gum-like resins and other solid material, indicating a marked reaction while the odour of the gasoline improved.

35 The cost of metallic sodium, and still more, the danger of using metallic sodium in a refinery (sodium reacts violently with water, and the hydrogen evolved ignites spontaneously), makes its use quite out of the question.

40 We therefore investigated the possibility of using loose compounds of sodium or other alkali metals which would show a similar effect to that of metallic sodium on the mineral oils without its disadvantages. We found such compounds as 45 the amides, alcoholates, amalgams or alloys of alkali metals to be refining agents for mineral oils. This refining action is due partly to removal of sulphur compounds and other undesirable substances which form compounds with the alkali 50 metal, and partly to the polymerization of unstable and therefore undesirable constituents to form gums or resins. These polymerized gums or resins are in part precipitated in the form of sludge together with the alkali metal compounds 55 formed during the process as mentioned above,

and in part remain dissolved in the oil. Preferably we redistill the oil treated according to our invention in order to free it from these polymerized and high boiling gums.

The following is an example of one of the most 60 useful methods of applying our invention for the refining of mineral oils by the action of alkali metal amalgams. It may be understood we are not confining ourselves to any of the particular features described in this example:

65 A solution of sodium or potassium amalgam in mercury is used as refining agent. The concentration of the amalgam is kept low enough to keep this solution liquid at the treating temperature. The mineral oil can be treated at normal or at 70 elevated temperature, preferably around 100° C. at which temperature the velocity of the reaction is sufficiently high. If the temperature is allowed to rise higher than 150° C. the refining action is 75 less effective and there is excessive reaction between mercury and the sulphur compounds in the oil, as a result of which mercuric sulphide is formed. As the temperature rises this compound is formed in increasing amounts thus making the recovery of the used mercury more complicated and the process less practicable. We therefore prefer to operate at a temperature not exceeding 100° C.

80 At a treating temperature of 100° C. a solution of amalgam in mercury containing more than 1.5% sodium or 2.0% potassium is liable to crystallize and this renders impracticable any circulation of the amalgam solution as described hereunder. We therefore operate with a solution of amalgam containing not more than 1% sodium 85 and preferably 0.7%. When potassium amalgam is used it is possible to operate with a slightly higher concentration of the alkali metal.

85 The use of a liquid solution of alkali metal amalgam in mercury is advantageous from several points of view: first, it can be manufactured cheaply by the electrolysis of alkali metal salt solutions, which manufacture is thoroughly established in the chemical industry. This avoids the necessity of preparing the amalgam by dissolving metallic sodium or potassium in mercury, a method which, because of fire hazard, is too 90 dangerous to employ in an oil refinery and, because of the high price of these metals, is entirely uneconomical as a means of refining gasoline. Second, the diluted amalgam does not react vigorously with water, and never such rate as to ignite the hydrogen evolved. Third, the dilute amalgam, being in the liquid state, may be 95 circulated in a continuous plant; as a liquid in 100

105 55 formed during the process as mentioned above, 110

motion it continuously presents a fresh surface to the oil and does not become coated with a layer of polymerized gums; consequently, the amalgam reacts more readily and more completely than a solid compound of similar nature. As a consequence of this more ready reaction, the refining in our process is completed in 5 to 10 minutes, whereas with solid metals or alloys the refining may take several hours.

10 For the sake of brevity this solution of alkali metal amalgam in mercury as specified above will be referred to in the future as "amalgam".

15 It will be understood that there are many different ways of carrying this invention into practice: all of which have as their object bringing the amalgam or other alkali metal compound into intimate contact with the mineral oil to be treated in a continuous and preferably counter-current manner. For example, the amalgam or other alkali metal compound may be brought into reaction by agitating it in contact with the cracked distillate in a single vessel or in a number of vessels arranged in series through which the amalgam and cracked distillate are made to pass in 20 a counter-current manner.

25 Alternatively, such a series of vessels may be replaced by a tower fitted with a number of superimposed trays, down which amalgam flows from tray to tray, and up which the distillate to be treated passes, arrangement being made in a manner well known to those skilled in such operations, to agitate the amalgam on the several trays, and to cause the distillate and amalgam to flow counter-current to each other with 30 as great a surface of contact as possible.

35 Alternatively, the amalgam may be reduced by atomizing or emulsifying, in any desired manner, to a fine state of subdivision, in which form it is introduced as a fine spray to the top of an 40 unpacked column, up which the distillate to be treated is caused to flow.

45 Alternatively, the mineral oil to be treated may be made to react with the amalgam in a compartment adjacent to or forming an integral part of the electrolytic cell in which the mercury cathode is so arranged that it is in contact on one hand with electrolyte, and on the other with the mineral oil to be treated. The mercury amalgam cathode may be agitated in any preferred way in order to facilitate reaction with the mineral oil. In this manner the mineral oil reacts directly with the cathode, which latter provides a supply of sodium continuously from the electrolyte to the oil.

55 The attached drawing illustrates more or less diagrammatically an apparatus which we have employed with good results for the application of our invention, using the principle of atomizing amalgam into the upper part of a vertical treating tower, up which the mineral oil to be treated is caused to flow. It will be understood that this is by no means the final form of our plant, as longer practice probably will require improvements and alterations without, however, changing the principle of our invention.

70 The mineral oil used in this example is a cracked distillate, previously subjected to the normal acid and soda wash treatment, and containing about 60% of gasoline fraction. The appropriate sections of the apparatus must therefore be capable of withstanding the pressures of 100-200 lbs. per sq. inch developed at the treating temperature.

75 The apparatus consists mainly of 1, preheater; 2, treating tower; 3, cooler; 4, water wash tower;

5, separator for sludge and mercury; 6, mercury storage tank; 7, electrolytic cell; 8, amalgam storage tank; 9, amalgam disperser; 10, mercury residue collector.

80 In the operation of this apparatus the cracked distillate to be treated is introduced through line 11 to pump 12 and pumped through preheater 1, which may consist in part of a heat exchanger, to treating tower 2, which may also be heated. It is met in this tower by a descending counter-flow of amalgam. The treated cracked distillate leaves the top of tower 2 by a side arm 13, and passes to the cooler 3, beyond which, at valve 14 the pressure is reduced to approximately atmospheric. It then passes to the bottom of wash tower 4, where it is washed in counterflow by water or dilute caustic soda from spray 15. The wash water and sludge which latter contains a little finely divided mercury or mercury sulphide are collected in receiver 10, while the treated oil leaves by line 16. The sludge from receiver 10 is worked up by any suitable process, as, for instance, by filtering, centrifuging, roasting, etc. to recover the small amount of mercury which it contains. The sludge collected at separator 5 is 90 separately washed with water and then subjected to the same recovery process. Any oil which separates during the washing of this sludge is returned to the cracked distillate storage. The treated cracked distillate is distilled, preferably 95 with open steam, for the preparation of gasoline of suitable endpoint, and the separation of any high boiling polymerized products.

100 Mercury stored in tank 6 is passed to electrolytic cell 7, where sodium amalgam is formed. This passes by gravity to storage tank 8, whence pump 17 passes it to the amalgam disperser 9, from which the dispersed amalgam falls directly into treating tower 2. The mercury, denuded of sodium by reaction with the undesirable constituents of the cracked distillate, collects at the bottom of tower 2, and is returned to storage tank 6 through the sludge separator 5.

110 In actual operation, more parts and instruments may be added which have been omitted here for the clearness of the description, as they can readily be added by those skilled in the art.

120 The outlet of the distillate from tower 2 is so arranged by means of the side arm 13 that none, or at worst very little, of the heavy amalgam can 125 pass out of the tower with the distillate.

130 The oils treated by any methods of our invention are distinguished by their pleasant odour, water white colour, colour stability in sunlight or darkness, and negative doctor test. In these respects especially, the cracked gasoline treated by our process is far superior to cracked gasoline refined by the usual processes.

We claim as our invention:

1. A process for the refining of oils comprising treating the oil with alkali metal amalgams whose alkali metal content does not exceed 1% of the amalgam.

2. A process for refining mineral oils, comprising treating the mineral oil with sodium amalgam whose sodium content does not exceed 1% of the amalgam.

3. A process for the refining of cracked petroleum oils, comprising treating the oil with a solution of sodium amalgam in mercury, the sodium content of which solution does not exceed 1.0% of the amalgam solution.

4. A process for the sweetening of cracked distillate comprising treating the cracked distillate continuously in counter current with finely di- 150

vided solution of sodium amalgam in mercury at a temperature not above 100° C.

5. A process for refining mineral oils comprising treating the mineral oil with sodium amalgam whose sodium content does not exceed 1% of the amalgam at about 100° C.

6. A process for the refining of cracked petroleum oils, comprising treating the oil with a solution of sodium amalgam in mercury, the so-

dium content of which solution does not exceed 1% of the amalgam solution, at about 100° C.

7. A process for the refining of oils comprising treating the oil with an alkali-metal amalgam whose alkali-metal content does not exceed 1% of the amalgam, at about 100° C.

EVAN CLIFFORD WILLIAMS.
